E. NESTLER

CLAMP

Filed Dec. 4, 1924

UNITED STATES PATENT OFFICE.

EMIL NESTLER, OF NEW YORK, N. Y., ASSIGNOR TO NESTLER RUBBER FUSING CO. INC., OF NEW YORK, N. Y., A CORPORATION OF NEW YORK.

CLAMP.

Application filed December 4, 1924. Serial No. 753,976.

This invention relates to clamps and more particularly to clamps designed for exerting pressure on tires or shoes or other articles within a mold during retreading or 5 other fusing or vulcanizing operation.

The invention has particular reference to apparatus for use in connection with the retreading of shoes or tires in which molds such as set forth in my copending application Serial No. 753,977 are used. These molds are heated in a steamless curing cabinet such as embodied in another copending application Serial No. 753,978, to fuse or vulcanize the rubber of the shoe or tire 15 while it is held under pressure by my improved clamp which latter forms the subject matter of this application.

A further object is to provide a clamp in which a yoke is employed and a single medium for exerting pressure on the yoke whereby a plurality of plungers or pressure feet are held under the desired pressure against a sand bag or like element within the shoe or tire so as to press the outer face 25 of the shoe or tire against the inner face of the mold. The invention, therefore, resides particularly in the construction and arrangement of elements constituting a clamp or pressure device, the broad idea 30 of which being to exert the maximum of pressure at a plurality of points by a single pressure means, or, in other words, to distribute the pressure where it will do the most good.

With these and other objects in view, the invention consists in certain novel features of construction and combinations and arrangements of parts which will be more fully hereinafter described and pointed out 40 in the claims.

In the accompanying drawings—

Figure 1 is a perspective view showing my improved saddle and yoke in their normal assemblage and as desired for use in 45 connection with a segmental mold;

Figure 2 is a view in transverse section through a segmental mold showing my improved clamping means in operative position thereon;

Figure 3 is a view in section on the line 3—3 of Figure 2;

Figure 4 illustrates a pair of pressure feet or plungers;

Figure 5 is a view similar to Figure 2 55 illustrating my invention in slightly modi-

fied form and as applied to a complete circular mold;

Figure 6 illustrates in detail the strap and saddle in the assemblage shown in Figure 5;

Figure 7 is a perspective view of my improved yoke.

Referring more particularly to Figures 1 to 4, inclusive, 1 represents a segmental mold having flanges or webs 2 at its sides, and said flanges or webs are provided with notches 3 for a purpose which will hereinafter appear. Within the mold 1 a tire or shoe 4 is located, and a bag or bags 5 preferably containing sand or other similar material 6 is or are located inside of the shoe.

7 represents the saddle of my improved clamp which is formed with openings 8 adjacent its ends for the reception of bolts 9. These bolts 9 are located in the notches 3 with the heads 10 of the bolts below the webs 2. The upper ends of the bolts are projected through the openings 8 and receive washers 11 and nuts 12, both located 70 thereon above the saddle 7.

The saddle 7 is provided with an upwardly projecting central post 13. This post may constitute an ordinary bolt having its head 14 located in a socket 15 in the lower face of the saddle. The upper end of this post 13 is screw-threaded and is projected through the center of a yoke 16 located at right angles to the saddle 7. A washer 17 is located 80 on top of the yoke 16 and a clamping nut 18 is screwed onto the post and against the washer.

The saddle 7 is provided at its ends with depending enlargements 19, preferably having sockets 20 in their lower faces. 21, 21 95 represent pressure feet or plungers which have extended base portions and are shaped at their lower faces so as to fit snugly against the sand bag 5 and exert pressure thereon. The upwardly projecting reduced portions 100 22 of the pressure feet 21 rest in the notches 20 in yoke 16 so that when the nut 18 is tightened it will force the yoke downwardly and exert pressure on the feet 21; hence pressure will be applied at two different 105 points by a single pressure member.

While I have illustrated a yoke which exerts equal pressure on two pressure feet, it is obvious that the invention is not limited to any particular number of pressure feet 110

as I wish to cover the idea broadly of a single pressure member or clamp which functions to exert pressure at a plurality of different points or stations so as to give the pressure where needed and produce the best results.

In Figures 5, 6 and 7, I illustrate a construction which is especially adapted for use in connection with a complete circular 10 mold such as indicated by the reference numeral 23. It is, of course, to be understood that this mold 23 is made in sections to facilitate the insertion or removal of the shoe or tire, and to this mold I secure a pair of 15 straps 24 located outside of the mold and secured thereto by a bolt 25 and nut 26. The free ends of these straps 24 are formed with slots 27 receiving the hooked ends 28 of a saddle 29. This saddle 29 has a screw-threaded post 30 at its center projecting through a yoke 31 similar to the yoke 16 above referred to, and this yoke 16 engages pressure feet 32 similar to the pressure feet 21 above described.

It will thus be noted that by reason of this construction the shoe or tire can be easily and quickly clamped in the mold and the desired pressure exerted at a number of different points so as to insure a complete 30 and uniform pressure throughout the shoe or, at least, throughout that portion thereof which contacts with the mold. Furthermore, the clamping assemblage can be readily removed so as to facilitate the operation.

Various slight changes and alterations might be made in the general form of the parts described without departing from my invention, and hence I do not limit myself to the precise details set forth but consider myself at liberty to make such slight changes and alterations as fairly fall with-

in the spirit and scope of the appended claims.

I claim:—

1. A clamp of the character described, comprising a saddle, means for connecting the saddle to the mold, a yoke connected to the saddle, and a plurality of pressure feet engaged by the yoke. 45

2. A device of the character described, comprising a saddle, means for connecting the same to a mold, a post carried by the saddle, a yoke receiving the post, clamping means on the post exerting pressure on 50 the yoke, and a pair of pressure feet engaged by the respective ends of the yoke. 55

3. A clamp of the character described, comprising a saddle adapted to be positioned transversely across a mold, means connecting the ends of the saddle with the mold, a central screw-threaded post on the saddle, a yoke extending longitudinally of the mold receiving the post, a clamping nut on the post engaging the yoke, and a pair of pressure feet engaged by the respective ends of 60 the yoke. 65

4. In combination with a mold adapted to receive a tire or shoe therein, a sand bag in the shoe or tire, a saddle extending transversely across and spaced from the mold, means connecting the saddle to the mold, a screw-threaded post projecting centrally from the saddle, a yoke extending longitudinally of the mold and at right angles to 70 the saddle and receiving the post, a clamping nut on the post adapted to move the yoke toward the saddle, said yoke having notched enlargements at its respective ends, pressure feet engaging a sand bag, and extensions on the pressure feet located in the 75 sockets of the yoke. 80
